UNITED STATES PATENT OFFICE.

JOHN P. C. FOSTER, OF NEW HAVEN, CONNECTICUT, ASSIGNOR OF ONE-HALF TO NEWELL A. THOMPSON, OF BOSTON, MASSACHUSETTS.

CAR.

SPECIFICATION forming part of Letters Patent No. 276,017, dated April 17, 1883.

Application filed February 19, 1883. (No model.)

To all whom it may concern:

Be it known that I, JOHN P. C. FOSTER, of New Haven, in the county of New Haven, and in the State of Connecticut, have invented 5 certain new and useful Improvements in Cars; and I do hereby declare that the following is a full, clear, and exact description thereof, reference being had to the accompanying drawings, making a part of this specification, in 10 which—

Figure 1 shows a perspective view of my improved convertible car arranged for use as a platform or lumber car. Fig. 2 shows a perspective view of the same arranged for use as 15 a coal or ore car, with the bottom shutters closed. Fig. 3 shows a longitudinal section of Fig. 2 on the line xx , with the shutters shown open in dotted or broken lines, and the end boards and their braces shown in dotted 20 lines as folded down. Fig. 4 shows a plan view of my car arranged as in Fig. 2, but with the shutters open.

Letters of like name and kind refer to like 25 parts in each of the figures.

The object of my invention is broadly to 30 provide a convertible car which, as occasion requires, may be readily changed from a platform to a dumping coal car and back again without the use of tools; and to this end it 35 consists principally in a car-body having sides made in several sections and hinged thereto so as to fold inward, and end boards likewise hinged, but adapted to swing backward and outward, substantially as and for the purpose 40 hereinafter specified.

It consists, further, in combining with the 45 dumping car-bottom the hinged side boards adapted to fold down upon the car-bottom to make an even and continuous floor over the same, substantially as hereinafter shown.

It consists, further, in combining with the 50 car-bottom, with its upright side stakes, the hinged side pieces and hinged end boards, with their supports, said end boards being adapted, when raised, to keep in an elevated position firmly against the said stakes the end sections of the hinged sides, substantially as herein- 55 after described and set forth.

It consists, further, in the combination of the 60 hinged end boards, with their hinged supports,

with the hinged side sections having abutting edges beveled, as described and shown, so that the end boards will not only keep the end sections of the sides in an elevated position, but also the middle sections, substantially as hereinafter more fully set forth. 55

It consists, further, in providing the car-bottom with hinged side pieces and end boards so attached that the end boards fold down below the end sections of the sides, so that the 60 side sections shall make a continuous and even floor for the support of lumber, &c., substantially as hereinafter specified.

It consists, further, in combining with the 65 dumping bottom of the car an opening and closing device applied to the center one of the series of shutters which are connected together by connecting-rods, and operating upon the other shutters of the series through the medium of such rods, substantially as hereinafter 70 shown and set forth.

It consists, further, in combining with the 75 shaft of the center shutter of the dumping bottom a segmental rack on the same, a pinion gearing with the rack, and an operating hand-wheel, substantially as and for the purpose hereinafter set forth.

It consists, further, in combining with the 80 shutter-bottom having opening and closing devices attached, and operating as hereinafter described, a locking device consisting of a hook or other device on the car-body, engaging with a pin, staple, or other suitable corresponding part attached to the shutters or their connecting-rod, at or near the center of the series 85 of shutters, substantially as hereinafter more fully described; and it consists, finally, in the general and special combinations and arrangements of parts, as hereinafter described, and specifically pointed out in the claims. 90

In the drawings, in which I have only shown so much of the car as is necessary to illustrate my invention, A A designate the external frame-work of the bottom or body proper of the car. The longitudinal brace-beams A' A' 95 are beveled off on their upper sides, as are also the cross-pieces O, to facilitate the discharge of the contents of the car when it is used for carrying coal and the like. The spaces between the end beams, A and A, and the pieces 100

O O are closed below, as shown, so as to form receptacles R, into which the hinged braces F F fold down out of the way of the hinged end boards, C C. These braces are hinged at their 5 lower ends to the bottoms of the receptacles.

The body of the car is provided with the usual upright side stakes, E E, and to the side beams the boards or side pieces, B B, are hinged so as to rest against the stakes when 10 swung up into an elevated position, as shown in Fig. 2.

To the body of the car, at some distance from the ends, are hinged the end boards, C C. They are so hinged at S S, below the plane of 15 the upper edges of the end and longitudinal brace-beams, and at such a distance from said end beams, that they fold down below and out of the way of the end sections of the hinged sides of the car, as shown in dotted lines in 20 Fig. 3. The end sections of the sides can then, when folded down, rest directly and evenly upon the upper surfaces of the beams A A and A' A'. The brace-beams A' A' are cut down, as shown in Fig. 3, from S to their ends to allow 25 the end boards to lie below the plane of the upper surface of the car-frame, as described.

As will be seen in Fig. 2, the end boards will, when raised, keep the end sections of the sides firmly in position against the upright 30 side stakes, and with the abutting edges of the side sections beveled, as shown in Fig. 4, the middle sections will be kept up firmly in place by the end sections, and tight joints made, whether the sides are up or down. By this 35 arrangement I avoid any necessity for braces or supports to keep the sides from falling inward. The end boards, when thus elevated, serve to keep all the side pieces also in an elevated position. The braces F F are therefore 40 the only ones needed for the whole car.

In my convertible car it is especially desirable to use the slat or shatter form of dumping bottom. The shutters G G are of the ordinary form, with their upper and lower edges 45 correspondingly beveled, so that they will slightly overlap and make a tight bottom for the car when the shutters are closed. (See Fig. 2.) They are journaled, pivoted, or hinged at their upper edges in the usual way to the 50 longitudinal beams of the car, and near their lower edges, at their ends, are connected together by rods H H. I have shown the shutters as hinged to the beams A' A' only; but I do not limit myself to such construction. The 55 rod or rock-shaft upon which the center shutter swings has attached to it a segmental lever-arm, N, carrying segment-rack L. Gear- 60 ing with this rack is a pinion, K, on the shaft M of the hand-wheel I. Said shaft is suitably journaled in the frame of the car. Where 65 the shutters are for any reason to be made large and heavy, I prefer to extend this shaft M through the frame of the car and place on the other end a second pinion, to gear with a corresponding segmental rack on an arm on that end of the pivot or rock shaft of the center shutter, as shown in Fig. 4. To lock the

shutters in a closed position I provide a hook on the side of the car-body, adapted to engage with a staple on the connecting-rod, about midway of the length of said rod, or to take over the rod at that point. A pin passing through a staple on the connecting-rod and into a hole in the side beam can be used, or any such as a sliding bolt engaging with the center shutter 70 or the segmental arm, or a spring-ratchet device to catch in a notch of the shutter or segmental arm as soon as the shutters are closed. A single one or a number of these devices can of course be used, as desired. In the drawings I 80 show three on a side—one near the middle and one at each end of the connecting-rod.

The double arrangement of operating pinion and segment, as shown in Fig. 4, together with the arrangement of two connecting-rods—one 85 at each side of the series of shutters—I find especially desirable where a close-fitting and a positive movement of all the shutters is wished.

With my improved car, as described and 90 shown, the change from a coal-car to a lumber-car and back again can be made very easily and expeditiously without the use of tools or the removal of any of the parts. As the different parts are all attached to the car, none 95 can be lost or misplaced. The multiplication of props or fastenings, where the sides are made in sections, is avoided, and an even and close-fitting floor is obtained when the sides are folded down. Because of the attachment of the closing mechanism for the dumping bottom directly to the center shutter of the connected series, all the shutters are closely and accurately 100 closed, and the springing or bending of the connecting-rods is avoided.

Where, as heretofore, the closing devices are attached at or near the end of the connected series of shutters, those at the end of the car farthest from the said closing devices fail to be closed properly on account of this bending 110 or buckling of the rods and the yielding or play of the parts throughout the length of the car. By my arrangement I avoid all this, and, if desired, I can adjust the shutters to any angle and be sure that they are all parallel. 115 The pinion and segment-rack connection enable me to make any such adjustment easily and positively, whether in opening or closing the shutters. Thus the rate of discharge of the contents of the car can be regulated and 120 made uniform throughout the length of the car.

Having thus fully set forth my invention, what I claim is—

1. The car-bottom provided with sides made 125 in several sections and hinged thereto so as to fold inward, and end boards likewise hinged, but adapted to swing backward and outward, substantially as and for the purpose set forth.

2. In combination with the car bottom or 130 body, with its upright side stakes, the hinged side pieces and hinged end boards, with their supports, said end boards being hinged in such a way that when raised they will keep the end

sections of the sides in an elevated position and firmly against the side stakes, substantially as and for the purpose set forth.

3. The combination of the hinged end boards, 5 with their props, with the hinged sections of the sides, having their abutting edges beveled, substantially as and for the purpose set forth.

4. The car-bottom provided with hinged sides and hinged end boards adapted to fold 10 down below and out of the way of the end sections of the sides, so that the sides can, when down, make a continuous and even floor, substantially as and for the purpose described.

5. The combination, with the dumping bottom 15 having the series of shutters, of the opening and closing mechanism applied to the center shutter of the series, and operating upon the others through the medium of a rod connecting the shutters, substantially as and for the 20 purpose set forth.

6. In combination with the pivot-shaft of the center shutter, the dumping bottom, the arm, the segment-rack, the pinion gearing with the rack, the hand-wheel, and the shaft thereof, substantially as and for the purpose described. 25

7. In a dumping car-bottom, the combination of a series of connected shutters, the open-

ing and closing device applied to the center shutter of the series, and actuating the others 30 through the medium of a rod connecting the shutters, and a locking device for fastening the shutters when closed, substantially as described and shown.

8. In a dumping car-bottom, the combination of a series of connected shutters, the opening and closing devices applied to the center shutter of the series, and operating upon the others through the medium of the rods connecting the shutters, and a locking device arranged at or near the middle of the series, substantially as set forth. 35 40

9. The convertible platform and coal car, constructed with hinged sides and end boards, props or supports for the same, and a dumping bottom composed of shutters with suitable closing devices, all adapted to operate substantially as and for the purpose set forth. 45

In testimony that I claim the foregoing I have hereunto set my hand this 15th day of February, 50 1883.

JOHN P. C. FOSTER.
